UNITED STATES PATENT OFFICE.

DANIEL W. BAGG, OF SOUTH NEW BERLIN, NEW YORK.

ENSILAGE-DISTRIBUTER.

1,182,619.

Specification of Letters Patent.

Patented May 9, 1916.

Application filed March 19, 1913. Serial No. 755,438.

To all whom it may concern:

Be it known that I, DANIEL W. BAGG, citizen of the United States, residing at South New Berlin, in the county of Chenango and 5 State of New York, have invented certain new and useful Improvements in Ensilage Distributers, of which the following is a specification.

This invention relates to ensilage distributers and has particular reference to distributers for the so-called pneumatic elevators employed to convey the ensilage from the cutter to the silo.

The principal object of this invention relates 15 sides in the provision of means whereby the ensilage may be uniformly distributed within in the silo.

A still further object contemplates the provision of means whereby the incoming 20 ensilage will be alternately distributed in the center of the silo and then scattered on the outer portion.

A still further object is to provide means whereby the alternation between the central 25 discharge and the scattering process may be automatically controlled.

The above and additional objects are accomplished by such means as are illustrated in the accompanying drawings, described in 30 the following specification and then more particularly pointed out in the claims which are appended hereto and form a part of this application.

With reference to the drawings, wherein, 35 I have illustrated the preferred embodiment of my invention as it is reduced to practice, and throughout the several views of which, similar reference numerals designate corresponding parts; Figure 1 is a side elevation 40 of the distributor illustrating in its assembled relation to an elevator chute; Fig. 2 is a bottom plan view; Fig. 3 is a vertical section; Fig. 4 is a detail view taken in a vertical plane and illustrating the means employed in rotatably mounting the distributor; and, Fig. 5 is a detail view in fragment of the ensilage chute; Fig. 6 is a top plan view of the cone.

Before proceeding with the description of 45 the drawings I wish it to be understood that while I have designed and shall proceed to

describe this device as an attachment for ensilage distributers it may nevertheless be readily and effectively applied to distributers for pneumatic elevators of any type.

55

Coming now to the description of the drawings, I have illustrated the distributor as applied to the discharge terminal of the elevator chute 1, the free terminal of which is bent to form a U-shaped discharge spout 2.

60

The distributor of my invention properly consists of three elements; the central discharge spout, the mechanism for scattering the ensilage centrifugally, and the means employed to alternate the discharge of the ensilage between the central spout and the centrifugal scattering device. Taking up these three elements in the order named, the central discharge spout 3 is preferably formed of a length of metallic tubing, the upper end of which is angularly offset and secured by any suitable fastening means to the interior of the mouth of the member 2 and on the inner side thereof. The major portion of the discharge spout 3 is disposed in alinement with the center of the mouth of the member 2.

65

Taking up as next in order the mechanism of the centrifugal scattering means, the numeral 4 designates a conical hollow casing 80 preferably formed of sheet metal and held in central relation to the elevator discharge chute by means of suitable securing straps 5 or any other desirable form of fastening means. In assembling the member 4 it is arranged so that the apex portion of the cone is disposed centrally of the discharge mouth of the member 2 and is projected a slight distance therein for a purpose to be hereinafter disclosed. A suitable opening 90 is formed in the casing 4 adjacent its apex for the obvious purpose of permitting the discharge spout 3 to be mounted in the desired position. A cylindrical casing 6 is mounted interiorly of the cone member 4 95 and is disposed with the free end projecting a slight distance beyond the base edge of the member 4, being held in spaced relation to the inner wall of the cone by the strap arms 7, which extend upwardly from the member 6 at diametrically opposite points and are secured to the casing 4 by

95

100

screws, rivets, or the like. The lower edge of the member 6 is bent upwardly and outwardly as at 8 to produce a circumferentially extending cross-sectionally channel 5 shaped, race-way for the roller bearing members 9. Mounted for rotation about the member 6 is the metallic band member 10, the upper and lower edges of which carry the integrally formed inwardly directed annular flanges 11 and 12 respectively, the flange 11 being mounted for movement over the ball member 9. This flange 12 is formed with gear teeth for a purpose to be hereinafter disclosed. As a 10 means for preventing the upward movement of the band 10, I have equipped the band with a pair of interiorly disposed diametrically arranged roller bearings 13 adapted to bear against the lower face of 15 the ball race 8. In effecting the centrifugal scattering of the ensilage I employ the distorted distributing blades 14 which are secured to the band 10 and project radially therefrom. These distributing blade members 20 are preferably four in number as illustrated in Fig. 2 and are twisted at their free ends to produce an angularly disposed surface, the function of which will be explained in the description of the operation 25 of the distributor. In conducting the ensilage from the elevator chute to the distributing blades, I employ the curved troughs 15, arranged in the nature of helices wound spirally upon the surface of the cone 30 4 and which in the absence of a better term I shall call spiral-helices. These trough members are preferably four in number terminating at different points in the periphery of the cone base, the discharge terminals 35 40 of the troughs being spaced an approximate distance of ninety degrees with respect to the circumference of the cone base, corresponding thus in their disposition to the arrangement of the distributing blades. 45 In rotating the band 10 to produce the desired scattering of the ensilage by the blades 14, I employ a vertically disposed countershaft 16, the lower terminal of which carries a gear wheel 17 arranged to mesh with 50 the gear teeth of the flange 13 and the upper end of which carries a bevel gear 18 arranged to engage the bevel gear 19 of the main drive shaft 20. The shaft 16 is mounted to operate through a suitable opening 55 formed in the cone 4 and is loosely journaled in bearings 21 carried by the elevator discharge spout 2. This countershaft 16 may be provided with a collar 22 arranged to engage the bearing 21 and to prevent the 60 vertical displacement of the shaft. The main drive shaft 20 is journaled in bearings 23 carried by the discharge spout 2 and the upper portion thereof.

As a means for alternately directing the

course of the ensilage through the central discharge spout and then down the trough members 15 to the distributing blades 14, I have equipped the discharge spout 2 with a baffle plate 24 indicated by dotted lines in Fig. 1. This baffle member consists preferably in a sheet of metal bent to form a cross-sectionally U-shaped member and is pivotally mounted interiorly of the spout 2 being attached to the outer side of the spout and disposed with the mouth of the 70 U opposed to the inner side of the member 2. From the upper edge of the member 24 and centrally thereof projects an upwardly directed arm 25 in the lower portion of which and adjacent its junction with the baffle plate is formed a laterally extending bore adapted to receive the pivot pin 26. A suitable opening is provided in the outer wall of the member 2 and through this opening the arm 25 is directed, the free end of 75 the arm being disposed for engagement by an eccentric pin 27 carried by a concentric disk 28 mounted on the shaft 20.

The actual construction of the several parts of my invention being thus disclosed, it is now arranged to present a brief description of the operation of the distributor. Briefly it is as follows:—The shaft 20 is driven at the required speed by any desirable motive power and communicates its motion to the band 10 through the intermediaries 19, 18, 16, 17 and 12. Simultaneously with the revolution of the band 10 and blades 14 attached thereto the baffle plate 24 is being swung pendularly by the action of the eccentric pin 27 against the free end of the arm 25. It will thus be seen that as the ensilage issues into the discharge spout it will by the action of the baffle 24 be first deflected into the central discharge spout 3 and then into the trough 15, the alteration in the path of travel of the ensilage being continued as long as the distributor is in operation. It is to be observed in this connection that if it be found desirable to change the timing of the movement of the baffle 24 to vary the ratio of the time periods in the two positions of the baffle it is only necessary to make a few minor changes in the mounting and drive gearing for the screw drive period. As the ensilage exits from the discharge spout 3 it will be deposited in the center of the silo and that portion of the ensilage which passes down the trough 15 will be subjected to the whirling motion of the blades 14, being thus scattered centrifugally in the direction of the outer portion of the silos. It is well to emphasize at this point the importance of the shaping of the distributor blades 14 for being twisted longitudinally and curved at their outer ends the ensilage as it issues from the trough 15 will strike a smooth surface, practically dis-

posed in parallel relation to and in horizontal alignment with the line of movement of the ensilage to the outer portion of the silo.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention what I claim as new and desire to secure by Letters Patent, is:—

20 1. In an ensilage distributor, a first distributor member designed to radially scatter the ensilage directed thereto, and a second distributor member within the first distributor member, said second distributor member 25 discharging at a point directly therebeneath.

2. In an ensilage distributor, a first distributor member designed to radially scatter the ensilage directed thereto, a second distributor member affixed to and within the 30 first distributor member to discharge at a point directly therebeneath, and means common to both members and operable to direct the ensilage alternately thereto.

3. In an ensilage distributor, a discharge 35 chute, a cone, a spout affixed to and within the cone, and means operable within the chute to alternately discharge ensilage on to the cone and into the spout.

4. An ensilage distributor including a discharge chute, a cone member disposed with its apex end extending thereto, a discharge 40 spout, terminating at a point, directly beneath the cone, and means operating within the chute to alternately discharge ensilage 45 onto the cone and into the spout.

5. An ensilage distributor including a discharge chute, a cone member, troughs arranged spirally upon the exterior of the cone, a discharge spout within the cone, and 50 means operating within the chute to alternately discharge the ensilage into the troughs and into the spout.

6. An ensilage distributor including a discharge chute, a cone disposed at the end 55 thereof, the apex of the cone extending into the extremity of the said chute, a discharge spout supported by the said cone, and extending upwardly into the chute at one side thereof, a plurality of curved troughs arranged 60 spirally upon the exterior surface of the cone, and means including a pivoted baffle plate supported by the said chute for alternately directing the ensilage upon the said troughs and into the discharge spout.

7. An ensilage distributor including a discharge chute, a cone disposed at the end thereof, a plurality of spirally arranged troughs mounted upon the exterior of the said cone, a cylindrical casing supported by said cone, and means including a plurality 70 of distributing blades supported by said casing adapted to distribute the ensilage as it flows from the said troughs.

8. An ensilage distributor including a discharge chute, a cone disposed at the end 75 thereof, a discharge spout supported by said cone and extending therethrough into the extremity of the said chute, a plurality of curved troughs arranged spirally upon the exterior surface of the cone, a baffle plate 80 pivotally supported by the said chute for alternately directing the ensilage into the troughs and into the said discharge spout, a cylindrical casing supported by the said cone, a band member rotatably mounted 85 upon the lower extremity of the said casing, and means including a plurality of distributing blades radiating from the said band member for distributing the ensilage as it flows from the said troughs.

9. An ensilage distributor including a discharge chute, a cone disposed at the end thereof, a discharge spout mounted upon the interior of the cone and extending through one side thereof and into the extremity of 95 the said chute, a plurality of curved troughs arranged spirally upon the exterior of the said cone, a baffle plate pivotally mounted upon the said chute, an arm projecting from the said plate upon the exterior of the said chute, and means adapted to engage the said arm for oscillating the said plate and alternately directing the ensilage upon the said trough and into the said discharge spout, of a cylindrical casing depending from the interior of the said cone, a band member rotatably mounted upon the lower extremity of the said casing, a plurality of distributing plates radiating from the said band adapted to distribute the ensilage as it flows from the said trough, and means including a plurality of gears and shafts supported by the said chute, for imparting motion to the said band from the arm operating means.

10. An ensilage distributor including a discharge chute, a cone disposed at the end thereof, a plurality of curved troughs arranged spirally upon the exterior surface of the cone, and means operable at the base of the cone to scatter the ensilage as it flows 110 from the troughs.

11. An ensilage distributor including a discharge chute, a cone member disposed at the end thereof, the apex of the cone extending into the extremity of the said chute, a plurality of curved troughs arranged spirally upon the exterior surface of the cone, a discharge spout supported by said cone and

extending into the extremity of the chute at one side thereof, the said spout passing through the wall of the cone and depending centrally therein, a baffle plate pivotally mounted upon said chute, and means oscillating said plate to alternately direct the ensilage onto said cone and into said spout.

In testimony whereof I affix my signature in presence of two witnesses.
